Primary Examiner — John Windmuller(74) *Attorney, Agent, or Firm* — Todd R. Miller(57) **CLAIM**

The ornamental design for a cable management main clip, as shown and described.

DESCRIPTION

FIG. 1 is a perspective view of a cable management main clip showing my new design;

FIG. 2 is an exploded side view thereof, illustrating the design has two separate parts;

FIG. 3 is a front view thereof;

FIG. 4 is a top view thereof; and,

FIG. 5 is a perspective view thereof in use with an optional cable tube and cables with elements in dashed lines forming no part of the claimed design.

The broken lines in FIGS. 1, 2, and 3 depict portions of the clip that form no part of the claimed design. The broken lines in FIG. 5 depict environment that forms no part of the claimed design.

1 Claim, 5 Drawing Sheets(56)
